UNITED STATES PATENT OFFICE.

CLARENCE W. MARSH, OF GREENWICH, CONNECTICUT, ASSIGNOR, BY MESNE ASSIGNMENTS, TO HOOKER ELECTROCHEMICAL COMPANY, OF NEW YORK, N. Y., A CORPORATION OF NEW YORK.

ELECTROLYTIC CELL.

1,075,363.

Specification of Letters Patent.

Patented Oct. 14, 1913.

Application filed January 15, 1912. Serial No. 671,189.

To all whom it may concern:

Be it known that I, CLARENCE W. MARSH, a citizen of the United States, residing at Greenwich, in the county of Fairfield and ⁵ State of Connecticut, have invented certain new and useful Improvements in Electrolytic Cells, of which the following is a specification.

This invention relates to electrolytic cells ¹⁰ of the diaphragm type, and especially to such as are adapted for the electrolysis of alkali-metal chlorides.

The object of the invention is to provide a construction of the above type which is ¹⁵ capable of efficient operation at low voltages, and which possesses a high ampere capacity in proportion to the space required for its installation.

For a full understanding of the invention, ²⁰ reference is made to the accompanying drawings, wherein:

Figure 1 is a plan view of one form of cell embodying the invention, one-half thereof being shown in section on the line ²⁵ I—I of Fig. 2; and Fig. 2 is an elevation of the same, one-half thereof in section on the line II—II of Fig. 1.

In said drawings, 1 represents a sheet-metal container, and 2 the bottom thereof, ³⁰ formed of cement composition, stoneware or other insulating material resistant to chlorin.

3 is the cathode of the cell, and is preferably constructed of sheet-steel, having ³⁵ closely-spaced elongated perforations 4. This cathode is flexed or bent to provide a series of substantially radial, vertically-extending pockets or recesses 5, with intermediate projecting portions 6; the said projecting portions 6 inclosing radial extensions or recesses ⁴⁰ 7 which are in open communication both at their sides and ends with the central or anode compartment 8 of the cell. The cathode is flexed outwardly ⁴⁵ above and below the radial pockets or recesses 5, and is preferably secured by riveting or otherwise at its upper and lower margins to the flanges 9 of the metal casing 1, thereby forming an efficient electrical connection therewith. The cathode connection to the cell may conveniently be secured directly to the upper flange 9, as indicated at ⁵⁰ 10. The upper and lower walls of the recessed pockets 5 are protected and rendered ⁵⁵ impervious and inactive in any suitable

manner, preferably as indicated by covering these portions of the plate with an insulating and inert plastic composition 11, interlocking with the plate through the perforations thereof. For this coating I may ⁶⁰ use cement, an insoluble condensation product of phenols and formaldehyde or a composition thereof, or the like.

12 is a bell-shaped cover for the cell, which may be of earthenware or cement ⁶⁵ composition, and fits closely within the upward extension of the cathode.

13 is a central aperture for the escape of chlorin gas.

The diaphragm 14, usually of asbestos ⁷⁰ paper or cloth or a combination of these, is applied closely to the inner face of the flexed cathode 3 and secured by cementing or otherwise to the non-conductive covering 11, as illustrated in Fig. 2. ⁷⁵

The anodes 15, usually of Acheson-graphite, are vertically disposed in the radial extensions or recesses ⁷ of the anode chamber, and extend upwardly through the cell-cover 12 being luted therein as shown at ⁸⁰ 16. Electrical connection to the anodes may be made as indicated by conducting bars 17 secured to the inner faces of the anode caps 18, and to a ring 19 of aluminum or copper which may be clamped to the ⁸⁵ anode bus-bar.

The electrolyte, usually a solution of sodium or potassium chlorid, is introduced into the anode compartment by a central supply-pipe 20, with which is preferably ⁹⁰ associated any suitable device for maintaining a constant level of liquid in the said compartment. In the form illustrated, this comprises an external supply-vessel 21, having a supply-pipe 22 for brine and an overflow ⁹⁵ 23 at the desired level. Means may be provided for adjusting this overflow in order to control the hydrostatic pressure of liquid in the anode compartment, or a series of overflows may be provided at differing levels, as is well understood in the art.

In operation, the solution undergoing electrolysis percolates through the diaphragm and cathode, into the external or ¹⁰⁵ cathode compartment 24, and the caustic solution may be withdrawn from this compartment by pipe 25, the hydrogen escaping through the vent 26, and being collected if desired. The cathode compartment ¹¹⁰

ment 24 may be filled with a mineral oil or other liquid immiscible with aqueous solutions, for purposes well understood in the art.

- 5 In the preferred construction, the radial extensions of the anode chamber broaden outwardly, whereby the maximum area of electrode surface is presented; and the anodes are shaped in transverse section in
 10 substantial conformity to the internal surfaces of these extensions. If desired, however, the radial extensions 7 may be substantially rectangular, in which case stock forms of graphite may be used as anodes.
 15 In case the cell is operated at relatively low current density, it is desirable that the exposed portions should be well covered with a suitable heat-insulating material, in order that the best working temperatures may be
 20 maintained.

I claim:

1. An electrolytic cell comprising concentric anode and cathode compartments, a pervious cathode and diaphragm separating
 25 said compartments, said cathode and diaphragm flexed or bent to provide recesses in open lateral and end communication with the anode compartment, and anodes disposed in said recesses.
- 30 2. An electrolytic cell comprising concentric anode and cathode compartments, a pervious cathode and diaphragm separating said compartments, said cathode and diaphragm flexed or bent to provide substantially radial recesses in open lateral and end communication with the anode compartment, and anodes disposed in said recesses.
- 35 3. An electrolytic cell comprising concentric anode and cathode compartments, a pervious cathode and diaphragm separating said compartments, said cathode and diaphragm flexed or bent to provide recesses in open lateral and end communication with the anode compartment, anodes disposed in
 40 said recesses, and means for maintaining a constant level of electrolyte in said anode compartment.
- 45 4. An electrolytic cell comprising concentric anode and cathode compartments, a pervious cathode and diaphragm separating said compartments, said cathode and diaphragm flexed or bent to provide substantially radial recesses in open lateral and end communication with the anode compartment, anodes disposed in said recesses, and means for maintaining a constant level of electrolyte in said anode compartment.
- 55 5. An electrolytic cell comprising concentric anode and cathode compartments, a pervious cathode and diaphragm separating said compartments, said cathode and diaphragm flexed or bent to provide correlated recesses communicating respectively with the anode and cathode compartments, the recesses communicating with the anode com-

partment being in open lateral and end communication therewith, and anodes disposed in the recesses which communicate with said anode compartment.

6. An electrolytic cell comprising concentric anode and cathode compartments, a pervious cathode and diaphragm separating said compartments, said cathode and diaphragm flexed or bent to provide correlated recesses communicating respectively with
 70 the anode and cathode compartments, the recesses communicating with the anode compartment being in open lateral and end communication therewith, and anodes disposed in the recesses which communicate with said anode compartment, the upper and lower walls of said recesses which communicate with the cathode compartment presenting
 75 non-conducting surfaces.

7. An electrolytic cell comprising a central anode compartment, a cathode compartment surrounding said anode compartment, a pervious cathode and diaphragm between said compartments, said cathode and diaphragm flexed or bent to provide recesses in
 80 lateral and end communication with said anode compartment, and anodes disposed in said recesses.

8. An electrolytic cell comprising a central anode compartment, a cathode compartment surrounding said anode compartment, a pervious cathode and diaphragm between said compartments, said cathode and diaphragm flexed or bent to provide substantially radial recesses in lateral and end communication with said anode compartment,
 95 and anodes disposed in said recesses.

9. An electrolytic cell comprising a central anode compartment, a cathode compartment surrounding said anode compartment, a pervious cathode and diaphragm between said compartments, said cathode and diaphragm flexed or bent to provide recesses in lateral and end communication with said anode compartment, anodes disposed in said
 105 recesses, and means for maintaining a constant level of electrolyte in said compartment.

10. An electrolytic cell comprising a central anode compartment, a cathode compartment surrounding said anode compartment, a pervious cathode and diaphragm between said compartments, said cathode and diaphragm flexed or bent to provide recesses extending radially inward and in open communication with the said cathode compartment, and anodes located in the said anode compartment between the walls of said recesses.

11. An electrolytic cell comprising a central anode compartment, a cathode compartment surrounding said anode compartment, a pervious cathode and diaphragm between said compartments, said cathode and diaphragm flexed or bent to provide recesses ex-
 125

tending radially inward and in open communication with the said cathode compartment, the upper and lower walls of said recesses presenting non-conducting surfaces, 5 and anodes located in the said anode compartment between the walls of said recesses.

12. A cell for the electrolysis of alkali salt solutions comprising concentric anode and cathode compartments separated by a substantially vertical pervious cathode and diaphragm, said cathode and diaphragm having pockets extending into said anode compartment and provided with imperforate upper and lower walls, and anodes disposed 10 in the recesses between said pockets.

13. A cell for the electrolysis of alkali salt

solutions comprising concentric anode and cathode compartments separated by a substantially vertical pervious cathode and diaphragm, said cathode and diaphragm having pockets extending into said anode compartment and provided with inclined imperforate upper and lower walls, and anodes disposed 20 in the recesses between said pockets.
